HEAT INSULATING LINING

Frank Christenson, Jamaica Estates, N. Y.

Application April 21, 1941, Serial No. 389,535

3 Claims. (Cl. 72—16)

This invention relates to a heat insulating lining for ducts, tanks, ovens, furnaces, flues or other metal surfaces which are subject to expansion and contraction due to changes of temperature.

An object of the invention is to provide a heat insulating lining of the above type having a facing of monolithic cement supported on an insulating blanket in such a manner that cracking of the cement due to expansion or contraction of the underlying metal surface is prevented.

Another object is to provide a simple, convenient and efficient heat insulating lining of the above type.

Various other objects and advantages will be apparent as the nature of the invention is more fully disclosed.

Although the novel features which are believed to be characteristic of this invention are pointed out more particularly in the claims appended hereto, the invention itself may be better understood by referring to the following description, taken in connection with the accompanying drawing in which a specific embodiment thereof has been set forth for purposes of illustration.

In the drawing:

Fig. 1 is a broken perspective view illustrating a lining embodying the present invention.

Fig. 2 is a transverse section showing the construction of the lining, and

Fig. 3 is an enlarged detail view showing the construction of the insulating blanket.

Referring to the drawing more in detail the invention is shown as applied to a wall 10 which may comprise a portion of a wall of a duct, tank, oven, furnace, flue or other metal surface which is subject to expansion or contraction and which is to be heat insulated. The wall 10 is shown as made of sheet metal and is provided with a plurality of pins 11 which are secured thereto by suitable means such as welding and act as securing for the blanket 12 of heat insulating material to be described.

The blanket 12 of heat insulating material may comprise a layer 13 of fibrous insulating material such as mineral wool, rock wool, slag wool, asbestos or the like, held by a wire screen 14 which extends around the entire blanket with overlapping ends 15 which may be secured by suitable means such as a wire 16 which is threaded therethrough. The blanket is thus self supporting and may be handled and applied as a unit. Wire pins or rivets 20 having heads 21, Fig. 3, are passed through the layer 13 and screen 14 and

are secured by washers 22 which may be adapted to snap over projections 23 formed on the pins 20.

In applying the insulating lining to the wall 10 in accordance with the present invention, the pins 11 are welded to the metal wall and are bent into upstanding position. The insulating blanket 12 is then applied thereover, in such a manner that the pins 11 pierce the same and extend therethrough. The projecting ends 11a of said pins are then bent over the outer surface of the blanket 12 for holding the same in place. A support for the cement, such as a layer 24 of expanded metal, or of other suitable metal lath, is then applied over the surface of the blanket 12 and the projecting ends 20a of the pins 20 are bent thereover to hold the same in place. An outer layer 26 of monolithic castable cement is then applied and is held in position by the layer 24 of expanded metal.

In the above-mentioned construction the pins 11 which are secured to the wall 10 do not contact or enter into the cement 26 and the pins 20 which hold the expanded metal layer 24 in place are not anchored to the wall 10 but are free for relative movement as the wall expands or contracts. Consequently, movement of the pins 11 is not transmitted to the cement layer 26 and does not produce cracks therein, but is taken up by the flexibility of the blanket itself.

The structure above described provides a fibrous blanket having high heat insulating properties coated with a monolithic cement which is supported under conditions suited to prevent cracking of the cement during use, even though the layer of monolithic cement covers a substantial surface area.

Although a specific embodiment of the invention has been described for purposes of illustration it is to be understood that various changes and modifications may be made therein without departing from the scope of the invention which is to be limited only in accordance with the following claims.

What is claimed is:

1. An insulating lining for a metal wall which is subject to expansion and contraction, comprising metal pins attached to the surface of said metal wall and extending outwardly therefrom, an insulating blanket on said wall and secured by said pins, additional pins extending through said blanket and secured thereto, said additional pins being free of said wall and adapted to move independently thereof, a layer of supporting material adapted to support a layer of cement, said additional pins extending through said layer of

supporting material and securing the same to said blanket, and a layer of cement covering said layer of supporting material and carried thereby, said first pins being free for relative movement with respect to said layer of cement whereby expansion or contraction of said metal wall may take place without cracking said layer of cement.

2. An insulating lining for a metal wall which is subject to expansion and contraction, comprising metal pins attached to the surface of said metal wall and extending outwardly therefrom, an insulating blanket on said wall and secured by said pins, said blanket comprising a layer of fibrous insulating material and a wire screen attached to the same to make a self supporting unit, additional pins extending through said blanket and secured thereto, said additional pins being free of said wall and adapted to move independently thereof, a layer of expanded metal adapted to support a layer of cement, said additional pins extending through said layer of expanded metal and securing the same to said blanket, and a layer of cement covering said layer of expanded metal and carried thereby, 25

said first pins being free for relative movement with respect to said layer of cement whereby expansion or contraction of said metal wall may take place without cracking said layer of cement.

3. An insulating lining for a metal wall which is subject to expansion and contraction, comprising an insulating blanket on said wall, said blanket comprising a layer of fibrous insulating material and a wire screen attached to the same to make a self supporting unit, pins attached to said wall extending through said blanket and bent over to secure the same in place, a layer of expanded metal over said blanket, additional pins extending through and secured in said blanket and bent over said expanded metal to hold the same in place and a layer of cement covering said expanded metal and carried thereby, said first pins being free for relative movement with respect to said layer of cement whereby expansion or contraction of said metal wall may take place without cracking said layer of cement, said additional pins being free of said wall and adapted to move independently thereof.

FRANK CHRISTENSON.
